UNITED STATES PATENT OFFICE.

ARTHUR TREVOR DAWSON AND GEORGE THOMAS BUCKHAM, OF WESTMINSTER, LONDON, ENGLAND, ASSIGNEES TO VICKERS LIMITED, OF WESTMINSTER, ENGLAND.

MOUNTING FOR AUTOMATIC GUNS.

1,272,393.

Specification of Letters Patent. Patented July 16, 1918.

Application filed October 14, 1915. Serial No. 55,793.

To all whom it may concern:

Be it known that we, Sir ARTHUR TREVOR DAWSON, Knight, and GEORGE THOMAS BUCKHAM, both subjects of the King of Great Britain, residing at Vickers House, Broadway, Westminster, in the county of London, England, have invented certain new and useful Improvements in or Relating to Mountings for Automatic Guns, of which the following is a specification.

This invention relates to cycle side cars of the kind adapted to carry automatic guns.

According to this invention we provide means whereby an automatic gun together with its tripod mounting is detachably connected in its firing position on the side car frame in such manner that the gun and its mounting can be readily removed bodily from the side car when desired and used in the ordinary manner with the mounting resting on the ground. The gun is preferably carried by the side car frame in such a position that its muzzle projects in a forward direction and the side car may have a seat for the gunner so that the gun can be fired without his having to leave the seat. The forward portion of the side car frame preferably carries a horizontal bed plate or support of approximately triangular formation. This bed plate may have at or near its corners three curved seatings adapted to receive correspondingly shaped portions of the mounting. The rearmost seating may receive the lug, on the rear portion of the mounting, to which the forward end of the rear leg or trail of the tripod is pivoted. The other two seatings may receive the machined portions of the pivoted ends of the front tripod legs. With the upper parts of these machined portions quick-release catches carried by the bed plate are adapted to engage in order to secure the gun and its mounting firmly in place.

Figure 1 is a side elevation showing more or less diagrammatically an automatic gun and its tripod mounting attached to the frame of a side car.

Fig. 2 is a plan of Fig. 1 but with the gun, its tripod mounting, and the aforesaid quick-release catches removed.

Fig. 3 is a side elevation of the aforesaid bed plate and the quick-release catches together with part of the tripod mounting, this view showing the bed plate reversed as

compared with Fig. 1, that is to say the rear part of the bed plate is at the left hand portion of the view instead of at the right hand.

Fig. 4 is a plan of Fig. 3, and

Fig. 5 is a side elevation of the front part of the bed plate as viewed in the direction of the arrow in Fig. 4.

A is the side car frame, and B is the gun. B', B' B² are respectively the two front legs and the rear leg or trail of the tripod mounting. b', b' represent the aforesaid machined portions of the pivoted ends of the front legs and b² represents the lug to which the forked end of the rear leg or trail is pivoted. C represents the aforesaid bed plate and c', c', c² represent the curved seatings thereon for the reception of the parts b', b', b². D, D represent the aforesaid quick-release catches. E represents the gunner's seat.

In the example shown each of the aforesaid quick-release catches D, D, comprises a lever D' pivoted at d' to the seating c' or to a bracket on the bed plate C. One arm of this lever is curved to bear against the upper surface of the machined portion b' of the pivoted end of the front leg B' and a suitable cushion or lining of leather or other suitable material may be carried by this curved arm. The other arm of this lever is adapted to engage with the lower end of a link or stirrup D² whose upper end is pivotally carried by an actuating finger-piece or arm D³ pivoted at d³ to the seating c' or to the aforesaid bracket, the pivot d³ being arranged below the point of connection of the link D² with the finger-piece or arm D³. This arrangement is such that by depressing the finger-piece or arm D³ until the link D² passes from one side to the other of the pivot d³ of the finger-piece or arm (i. e., until the parts pass over their dead center) the pivoted lever D' will be firmly held in its clamping position.

In placing the gun and mounting in position on the side car frame the front legs of the tripod are first folded against the rear leg or trail as shown in Fig. 1, straps being used if necessary to keep them in this position. The spade B³ of the rear leg is caused to engage with a suitable abutment on a transverse member b³ of the side car framing and the mounting is then lowered on to the aforesaid seatings. The quick-re-

lease catches D, D are then moved to the operative position and the gun is ready to be fired when in this position. In order to detach the mounting to enable the tripod to be placed on the ground the above stated operations are reversed.

What we claim and desire to secure by Letters Patent of the United States is:—

1. The combination with a cycle side car, 10 of an automatic gun, a mounting for the gun having three protuberances, a bed plate having three curved seatings adapted to receive said protuberances, and means for detachably connecting the mounting to the 15 said bed plate with the muzzle of the gun projecting in a forward direction.
2. The combination with a cycle side car, 20 of an automatic gun, a mounting for said gun comprising a pair of front tripod legs pivoted at their upper ends to the upper part of the mounting, a lug on the upper part of the mounting, a rear tripod leg pivoted to said lug, a bed plate of triangular formation at the forward part of the side car frame having three curved seatings, two 25 of which are adapted to receive the curved pivoted ends of the front tripod legs and the other is adapted to receive the lug to which the rear tripod leg is pivoted, and quick 30 release catches for retaining the said curved pivoted ends in position on their seatings.
3. The combination with a cycle side car, 35 of an automatic gun, a mounting for said gun comprising a pair of front tripod legs pivoted at their upper ends to the upper part of the mounting, a lug on the upper part of the mounting, a rear tripod leg pivoted to said lug, a bed plate of triangular formation at the forward part of the side 40 car frame having three curved seatings, two of which are adapted to receive the curved pivoted ends of the front tripod legs and the other is adapted to receive the lug to which the rear tripod leg is pivoted, and quick 45 release catches for retaining the said curved pivoted ends in position on their seatings,

together with an abutment on the side car framing for supporting the end of the said rear tripod leg.

4. The combination with a motor cycle, 50 controlled by a driver, of a cycle side car comprising a one-wheeled chassis, means for connecting said chassis to the cycle, a support on said chassis, a breech loading gun and its tripod mounting pivotally mounted 55 on the said support, a gunner's seat also carried on said chassis and located below the breech end of said gun, the position of said seat relatively to the breech end of the gun being such that said gun can normally be 60 operated by the gunner while the carriage is in motion and without its being necessary for either the motor cycle driver or the gunner to leave his seat, and means for detachably connecting said gun and its tripod 65 mounting to said support for the purpose specified.

5. The combination with a motor cycle, 70 controlled by a driver, of a cycle side car comprising a one-wheeled chassis, means for connecting said chassis to said cycle, a support on said chassis, a breech loading gun and its tripod mounting pivotally mounted on the said support, a gunner's seat also carried on said chassis and located below 75 the breech end of said gun, the position of said seat relatively to the breech end of the gun being such that said gun can normally be 80 operated by the gunner while the carriage is in motion and without its being necessary for either the motor cycle driver or the gunner to leave his seat, and quick release catches for detachably connecting the gun and its tripod mounting to the said support.

In testimony whereof we affix our signatures in the presence of two witnesses.

ARTHUR TREVOR DAWSON.
GEORGE THOMAS BUCKHAM.
